COMBINED STOKER AND FIREDOR

Paul A. Ketchpel, Bergenfield, N. J., assignor to
The Standard Stoker Company, Incorporated,
a corporation of Delaware

Application October 6, 1931. Serial No. 567,215

17 Claims. (Cl. 110—181)

This invention relates to firedoors which are employed to close the firing opening of a furnace and more particularly to that type of firedoor which forms a roof or hood portion of a stoker 5 discharge conduit adapted to deliver fuel into the furnace through the firing opening.

An object of the invention is the provision of a novel stoker conduit and firedoor construction particularly adapted for use with furnace firing 10 openings of minimum dimensions.

It is also one of the objects of this invention to provide a firedoor arranged to move up and down which may be operated either manually or by power means and which comprises a plurality 15 of flexibly related segments forming a rearwardly and downwardly curving portion of the firedoor which serves as a roof for a stoker discharge conduit communicating with the firing opening.

It is also an object of this invention to provide 20 in a stoker of the scatter feed type that delivers fuel into the furnace through the firing opening, which opening is covered by a pressure fluid operated door serving also as a roof for the stoker discharge conduit delivering mouth, a novel control mechanism which is arranged to control the 25 operation of the stoker in timed relation with the pressure fluid means for operating the firedoor. By this arrangement, whenever the firedoor is to be opened by pressure fluid means for 30 manual firing or for inspection of the furnace, the operation of the stoker fuel conveying means is interrupted so that the fuel at the stoker discharge conduit delivery mouth may not fall on to the cab deck when the door is opened. This 35 phase of the invention also contemplates the provision of added means in the control mechanism whereby the fuel at the stoker discharge conduit delivery mouth above the level of the distributing means is projected into the furnace prior to the 40 opening of the firedoor, thereby allowing the full use of the firing opening for inspection or manual firing of the boiler.

On the drawings

Fig. 1 is a central vertical longitudinal view 45 of the rearward portion of a locomotive showing the invention in position with portions broken away;

Fig. 2 is an elevation of the boiler backwall showing the invention partly in section;

Fig. 3 is a view similar to a portion of Figure 2 showing the control mechanism in one of its phases;

Fig. 4 is an enlarged vertical longitudinal section view through the backwall and the firing

opening showing the construction of the novel flexible firedoor;

Fig. 5 is a sectional view of a control valve; and

Fig. 6 is a sectional view showing the latch arrangement for holding the door in its uppermost position.

The invention is shown as being applied to a locomotive A having a firebox 10, the grates 11 and a firing opening 12 in the firebox backwall 13. Extending rearwardly of the backwall 13 is a cab 14, provided with a deck 15 which is below the lower marginal edge of the firing opening 12.

A stoker generally designated at B extends forwardly from the tender (not shown) and includes 70 a conduit 16 leading from the tender fuel bin having a screw conveyor 16a therein for advancing fuel therethrough and riser conduit 80 including a curved nozzle or discharge conduit 17 secured to the backwall 13 and a head portion 75 81 surmounting the discharge conduit 17 and arranged to discharge fuel into the firebox through the firing opening 12. The conduit 16 and the discharge conduit 17 are flexibly related at their adjacent ends as at 82 to permit articulation 80 therebetween. A distributor plate 19 extends forwardly from the discharge conduit 17 through the firing opening 12 and, in conjunction with a pressure fluid head 20, distributes fuel to all parts of the fire. The pressure fluid head 20 is located 85 rearward of the distributor plate 19 and is arranged to issue blasts of pressure fluid through the jet openings 21 in its front face 22. Lead lines 23 supply pressure fluid such as steam to the distributor head 20. The discharge conduit 17 90 is truncated at its upper portion as at 24 in substantially the plane of the distributor plate 19 to form a delivery mouth 25 which flares laterally to substantially the width of the firing opening 12.

A firedoor C for the firing opening 12 is arranged to move up and down and in its lowered position assumes a rearwardly and downwardly curving configuration indicated at 26 and rests upon the truncated portion of the discharge conduit forming a closure therewith for the opening 12 against outside exposure. In this position the firedoor C extends a sufficient distance above the plane of the distributor plate 19 to allow the column of fuel advancing through the discharge 105 conduit to assume its angle of repose with the front face 22 of the distributor head 20.

The movable door C comprises a flat plate-like portion 27 and a flexible portion 28 depending therefrom. The flexible portion 28 includes the 110

segments 29 which have their adjacent faces curved and are secured to a flexible member 30 as by means of the rivets 31. The opposite ends 32, 32a of the plate-like portion 27 and 33, 33a of the segments 29 are received in the races 34, 34a in the sidewalls 35, 35a, respectively, which are formed as a part of the door frame F secured to the backwall 13 for receiving the sliding door C. The sidewalls 35, 35a extend rearwardly from the lower portion of the door frame F and are spaced apart a distance equal substantially to the width of the stoker discharge conduit mouth portion. The point where these side walls extend rearwardly from the lower portion of the door frame in effect constitutes the extreme upper edge of the fuel supporting portions of the side walls of the discharge conduit and the extensions thereabove form a frame for the door C and do not function as fuel supporting walls of the conduit. Adjacent this point and near the upper marginal edge of the firing opening a transverse bar 82 forms a tie between the side wall extensions constituting the door frame F. The contiguous edges of the upper end of the rear wall, the transverse bar 82 and that portion of the side walls 35, 35a therebetween form an aperture in the upper side of the discharge conduit. It will be noted that the horizontal distance between the longitudinal extremities of the aforesaid aperture is greater than the longitudinal horizontal distance across the feed conduit adjacent the lower extremity of said aperture, which lower extremity is, of course, the upper edge of the rear wall of the conduit and the other extremity is formed by the transverse bar 82. The door C forms a movable closure for the aperture and as such also may be considered as a firedoor for the firing opening 12.

The door C may be power operated and for this purpose a motor cylinder 36, housing a piston 37 is attached to the door frame F. The piston 37 is operatively connected to a lever 38 which is fulcrumed as at 39 and connected to the flat plate-like portion 27 of the door C as by means of the roller 40 which is received by the channelled portion 41 of the lever 38. A handle 42 extending outwardly from said lever 38 is provided for the manual operation of the door C which may be retained in an opened position by means of the latch 43 engaging the lug 43a formed with said door. Pressure fluid, such as compressed air, is supplied to the motor cylinder 36 by the lead 44 for power operation of the door.

A control mechanism, generally indicated at 45 controls the supply of compressed air for the opening of the door C and is also arranged to interrupt the operation of the stoker in a manner as will now be described.

The control mechanism 45 comprises a body 46 encasing the chambers 47 and 48 which house the valves 47a and 48a respectively. A lead 49 supplies compressed air to the chamber 47 for admission to the lead line 50 when the valve 47a is raised as by means of the lever arm 51 movable by pressure on the pedal arm 52. Steam is supplied by the pipe 53 to the chamber 48 from whence it passes into the pipe 54 for supplying steam for the stoker prime mover, diagrammatically shown at M. The valve 48a is provided with a stem 55 to which is secured a spring 56. The spring 56 rests on an extension 51a of the lever arm 51 and is of a suitable strength, to cause the valve 48a to be seated, against the pressure in the steam pipe 53 when the lever arm 51 is raised.

Suppose now, that the stoker is in operation delivering fuel to the firebox and the door C is closed, and the fireman wishes to open the door. He depresses the pedal arm 52, causing the free end of the lever arm 51 to be raised. The lever arm 51 in its upward movement contacts the spring 56, pushes it, together with the attached valve stem 55 and valve 48a upwardly to seat the valve 48a, thereby interrupting the passage of steam from the steam supply pipe 53 to the pipe 54 and as a result halting the operation of the stoker. Further, pressure of the pedal arm 52 will cause the lever arm 51 to compress the spring 56 so that the lever arm 51 may travel upwardly a sufficient distance to unseat the valve 47a, allowing compressed air to pass from the lead 49 into the lead 50 for opening the door C directly, or, as shown in the drawings and hereinafter described more in detail, to supply compressed air to the motor cylinder 36 through a regulating valve 57 which serves to connect pressure fluid lines 53 and 59, each of which branches from the steam pipe 53 and to connect the compressed air lines 50 and 44.

The regulating valve 57 comprises a cylinder 70 housing a valve member 71 therein which is provided with the piston 60 and the stem 61 recessed as at 62 so that when the piston 60 is moved upwardly, the pressure fluid lines 58 and 59 are in communication with each other. A fluid line 63 branches from the pressure fluid line 58 and communicates with a chamber or header 64 at the rear of the discharge conduit 17, the header 64 being arranged to issue blasts of pressure fluid forwardly therefrom at about the plane of the distributor plate 19 for projecting into the firebox the column of fuel which is above the truncated portion 24 of the discharge conduit, prior to the opening of the firedoor C.

Branching from the steam pipe 53 is a lead 65 which supplies steam to the pressure fluid head 20 as through the lead lines 23 which branch from said lead 65. The fluid leads 63 and 65 are connected by a check valve 66 which normally is seated as shown in Figure 2 by the pressure in the lead 65. The fluid leads 58, 59 and 65 are provided with the valves 58a, 59a and 65a respectively, the valve 58a being normally closed, and being opened only when it is desired to project forwardly the fuel in that portion of the discharge conduit mouth portion rearward of the steam head independently of the use of the regulating valve. The valve 59a is preferably opened to admit a higher pressure of steam into the lead 59 and hence into the recess 62 of the valve 65 stem 61 than is allowed to pass through the valve 65a of the pressure head lead 65.

The cylinder 70 of the regulating valve 57 is covered by a cap 72 having an atmospheric opening 73 in the flange 74 communicating with said cylinder and is provided with a recess 75 suitable to accommodate the extension 77 of the piston 60. A controllable valve 78 is threaded into the cap 72 to control the size of the atmospheric opening 79 which is in communication with said recess 75.

By referring to Figures 2 and 3 and 5, it will be observed that when the pedal arm 52 is depressed to interrupt the operation of the stoker driving engine, a further pressure thereon will cause the lever arm 51 to raise the valve 47a providing communication between the compressed air line 49 and the lead 50 and permitting compressed air to enter the lead 50 from the lead 49 thereby raising the piston 60 and the stem 61 thereof. The upward movement of the piston 60 will then

connect the pressure fluid leads 58 and 59 causing the relatively high pressure of steam to enter the branch lead 63 for supplying steam to the chamber 64 for projecting into the firebox the column of fuel above the distributor plate 19 at the rear thereof. At the same time, the higher steam pressure in the lead 63 will unseat the check valve 66 as shown in Figure 3, thereby admitting steam to the chamber 64.

contiguous edges of said rear and side walls defining an opening extending upwardly and forwardly from the upper edge of said rear wall and terminating near the upper marginal edge of said firing opening, and a door comprising flexibly related segments arranged to form a closure for said opening and to be raised from covering position to expose the firing opening.

5 column of fuel above the distributor plate 19 at the rear thereof. At the same time, the higher steam pressure in the lead 63 will unseat the check valve 66 as shown in Figure 3, thereby admitting higher steam pressure to the pressure fluid head 20 for assisting the projection of fuel into the firebox. A short interval after the valve member 71 in its upward movement has effected communication between the leads 58 and 59 through its recessed portion 62, it effects in its 10 continued upward movement, communication between the compressed air lines 50 and 44 when the piston 60 is raised above the point at which the line 44 opens into the cylinder 70. Communication between the lines 50 and 44 being established, compressed air passes from the line 50 into the line 44 and thence to the motor cylinder 36 for opening the door C.

It will be understood that the upward movement of the piston 60 from the position shown in Figure 2 to that shown in Figure 3 will be almost instantaneous due to the atmospheric opening 73 thus allowing the pressure fluid leads 58 and 59 to be connected quickly, permitting steam to pass from the supply pipe 53, through the lead 59, into the cylinder 70, then successively through the leads 58 and 63 to the header 64, from which steam is emitted for projecting the fuel forwardly which is rearward and above the plane of the distributor plate. The further upward traverse of the piston 60 will be at a slower rate of speed commensurate with the size of the atmospheric opening 79 as controlled by the valve 78 for allowing the air in the recess 75 to be compressed and evacuated by the upward movement of the extension 77 of the piston 60. Thus, after the pressure fluid leads 58 and 59 are quickly connected, they will remain in communication with each other for an interval of time, as regulated by the valve 78, sufficient to project all of the fuel forwardly which is rearward of the distributor plate and above the plane thereof.

From the foregoing it will be apparent that I have provided a new and useful upwardly and downwardly movable firedoor having a flexible portion which is especially adapted for use as a hood or roof of a stoker discharge conduit mouth portion. The firedoor being arranged so that when the firedoor is moved vertically, the lower portion thereof, which is necessarily flared rearwardly to serve as a roof for the stoker discharge mouth, is arranged to be raised in the manner as described, thereby occupying but little space in the cab rearward of the boiler backwall.

It will also be apparent that I have provided a novel stoker control mechanism in conjunction with a pressure fluid operated door which is particularly useful and advantageous for use with stokers which discharge fuel through the firing opening closed by a firedoor forming a roof for said stoker discharge mouth.

While but one form of the invention is illustrated, others are contemplated within the scope of the appended claims.

I claim:

70 1. In a firebox having a wall provided with a firing opening, a stoker conduit communicating with said opening, said conduit including a rear wall and side walls extending upwardly beyond the upper edge of said rear wall and above the
75 lower marginal edge of said firing opening, the

- and forming a closure for the opening defined by the contiguous edges of said rear and side walls. 13. In a firebox having a wall provided with a firing opening therein for hand and stoker firing, a stoker conduit in communication with the lower portion of said opening, said stoker conduit at its delivery end including a rear wall and side walls extending beyond said rear wall, said side walls having edges of their extended portions curving upwardly and forwardly from the upper edge of said rear wall to points adjacent the firing opening, and a fire door having an upper and a lower portion, the upper portion of said firedoor being substantially parallel with said firebox wall and forming a closure for the opening defined by the contiguous edges of said rear and side walls. 14. In a firebox having a wall provided with a firing opening therein for hand and stoker firing, a stoker conduit in communication with the firing opening, the stoker conduit having side walls including fuel supporting portions which extend above the upper terminus of the rear wall of the stoker conduit and above the lower marginal edge of the firing opening, the upper edges of said fuel supporting portions of the sidewalls terminating below the upper marginal edge of the firing opening, and a firedoor having an upper and a lower portion, the upper portion of said firedoor forming a closure for the upper portion of said firing opening above the upper edges of said fuel supporting portions of the sidewalls and the lower portion of said firedoor extending rearwardly from said upper portion of the firedoor and forming a wall of the stoker conduit between said fuel supporting portions of the sidewalls and forward of the upper terminus of said rear wall. 15. In a firebox having a wall provided with a firing opening therein for hand and stoker firing, a stoker conduit in communication with the firing opening, said stoker conduit at its delivery end including a rear wall and side walls, said sidewalls including fuel supporting portions extending beyond and above the upper edge of said rear wall and above the lower marginal edge of said firing opening but terminating below the upper marginal edge thereof, the conduit opening forwardly into said firing opening between said fuel supporting portions of the sidewalls and opening upwardly between said fuel supporting portions of the sidewalls and the plane of the firebox wall and the upper edge of the rear wall, said last named opening being defined by the contiguous edges of the rear wall and the fuel supporting portions of the side walls, and a firedoor having an upper and a lower portion, the upper portion of said firedoor forming a closure for the upper portion of said firing opening above the upper edges of said fuel supporting portions of the sidewalls and the lower portion of said firedoor extending rearwardly from said upper portion of the firedoor and forming a closure for the opening defined by the contiguous edges of said rear wall and said fuel supporting portions of the sidewalls. 16. In a firebox having a wall provided with a firing opening therein for hand and stoker firing, a stoker conduit communicating with the firing opening, said stoker conduit at its delivery end including a rear wall and side walls having fuel supporting portions extending beyond and above the upper edge of said rear wall and above the lower marginal edge of said firing opening but terminating below the upper marginal edge thereof, the conduit opening forwardly into said firing opening between said fuel supporting portions of the side walls and opening upwardly between said fuel supporting portions of the side walls and the plane of the firebox wall and the upper edge of said rear wall, said last named opening being defined by the contiguous edges of the rear wall and the fuel supporting portions of the side walls, and a firedoor having an upper and a lower portion, the upper portion of said firedoor being substantially parallel with said firebox wall and forming a closure for the upper portion of said firing opening above the upper edges of said fuel supporting portions of the sidewalls and the lower portion of said firedoor extending rearwardly from said upper portion of the firedoor and forming a closure for the opening defined by the contiguous edges of said rear wall and said fuel supporting portions of the sidewalls. 17. In a firebox having a wall provided with an opening therein for hand and stoker firing, a stoker feed conduit extending upwardly and forwardly to said firing opening, said conduit having in its upper portion opposite and remote from said firing opening an aperture constituting a manhole for entry into the firebox and for hand firing of fuel, said aperture extending downwardly below the level of the upper half of said firing opening and upwardly above the level of the lower half of said firing opening, said conduit having sidewalls extending upwardly above the lower marginal edge of said aperture and above the level of the lower half of the firing opening and spaced apart a distance to include the firing opening therebetween, the horizontal distance between the vertical planes passing through the longitudinal extremities of said aperture being greater than the longitudinal horizontal distance across said conduit adjacent the lower extremity of said aperture, a door closing said aperture extending forward of the transverse vertical plane passed through the interior upper edge of the forward wall of the feed conduit.
